UNITED STATES PATENT OFFICE

EWALD UFERT, OF TRENTON, NEW JERSEY

PARLOR ILLUMINATION AND PORTABLE AMUSEMENT DEVICE

Application filed June 10, 1931, Serial No. 543,451. Renewed October 14, 1932.

The subject-matter of the present invention relates generally to parlor illumination and portable amusement devices wherein the combined advantages of illumination and amusement may be provided for within a single unit.

As will presently appear the invention is featured by the provision of suitable pedestal supporting means for a radio cabinet, or the like, said means further serving to carry certain illuminating elements and a fanciful and ornamental shade.

Another object is to provide means to support an amusement device, in the form of a radio, or the like, said radio in turn being capable of carrying a removable closure member adapted to serve as a writing desk or table top.

Still another object of the invention resides in the provision of a closure member adapted to removably carry a tubular member the latter supporting a loud speaker unit at its upper end and to serve as a conduit for the usual wiring necessary to a lamp arrangement and an amusement device, such as a radio.

A still further object is to provide a tubular member capable of supporting the usual illuminating means of a lamp and also a loud speaker unit, said unit in turn serving as a support of an ornamental shade for the lamp arrangement.

A further feature of the invention is to provide a device of the above-mentioned character which is substantially dual in its function and which may be positioned at any desired place in a room for the purposes aforesaid.

Still another aim of the invention resides in the positioning of a loud speaker unit within a shade whereby the volume and clarity of the sounds emanating therefrom are cushioned by the usual ceiling of a room, the vibrations being thus cushioned and confined by the side walls of the room to materially increase harmony and mildness of tone.

Another feature of the invention is to provide an article of beauty and decorative value, and which occupies but a minimum

amount of space and which possesses great utility.

With these objects in view, together with others which will appear as the description proceeds, the invention resides in the novel formation, combination, and arrangement of parts, all as will be described more fully hereinafter, illustrated in the drawing, and particularly pointed out in the claims.

In said drawing:

Figure 1 is a front elevation of my parlor illumination and portable amusement device.

Fig. 2 is an elevation of the same as viewed at right angles to Fig. 1, the upper portion being shown as sectioned substantially on the line 2-2 of Fig. 1.

Fig. 3 is a plan view thereof.

Referring now more in particular to the accompanying drawing, wherein like characters of reference denote similar parts throughout the several views, let 5 indicate the base or supporting means of my improved structure, said base being formed of suitable light-weight material and cast to the configuration indicated. In order to decrease the weight of the complete device in order that the same may be readily carried from place to place, the bulbous portion 6 may be stamped or spun together with the neck portion 7, the upper portion of the latter being flanged, as indicated at 8, to support the cabinet 9, as by means of bolts 10, or the like.

Said cabinet 9 is adapted to house the usual parts comprising a radio set of any suitable make, said radio serving as an amusement device, and it will be understood that the latter term is used in its broadest sense as obviously no claim is made to any particular form of radio nor its mode of operation. As shown in Fig. 2 the edges of the front and rear walls of said cabinet are rabbeted, as indicated at 11, for the reception of depending tongues 12 extended from the under surface of the closure 13, thereby providing means whereby said closure may be slidably associated with said cabinet to completely close the open top portion thereof or to permit access thereto when it be-

comes necessary to adjust or repair the parts of the radio set. It will be appreciated that said closure 13 may be of suitable dimensions to serve as a table top or a writing desk thereby increasing the utility of the article. Said closure 13 also serves as a support for the upper portion of my improved device, and as shown in Fig. 2, said closure is provided with an aperture 14 for the threaded reception of the shank 15 of the tubular member 16, the upper end of said member 16 being preferably flared, as indicated at 17 to support a loud speaker unit 18 directed upwardly. Said tubular member 15 thus serves to house the usual wires leading from the radio set to the loud speaker unit 18, said wires passing through the orifice 19 in said shank 15 and thence through said tubular member to said speaker unit 18, thereby concealing the connections between the aforementioned articles. The flared portion 17 of said member 16 may be provided with the usual sockets 20 to support lamps 21 to provide illuminating means, and naturally the wires extending to said lamps or sockets may be concealed within said tubular member.

The shade 22 may be fashioned from suitable material and decorated to present an ornamental appearance and as shown in the drawing a suitable fringe 23 may be added to further enhance its decorative value. Said shade will be provided with a central top opening defined by a rim 24, the latter abutting the periphery of the loud speaker unit 18, as shown in Fig. 2, thereby supporting said shade in the position indicated.

From the foregoing it is obvious that I have provided an article possessing great utility in that the same performs the dual function of illuminating means and amusement means. The article is portable and may be placed in any desired position, yet the same is exceedingly compact and thus occupies but a minimum amount of space. As the speaker unit is directed upwardly the vibrations tend to be cushioned by the ceiling of a room and confined by the side walls of the latter so that the tones are modulated and modified by this effect.

In shipping the article, said tubular member may be readily detached from the closure 13, and the latter may be removed to afford convenient access to the radio cabinet.

Further, the cabinet may be removed by removal of the bolts 10, thus permitting the transporting of the radio set per se to a workshop for repairs.

While the present is a disclosure of the preferred embodiment of the invention, it is to be understood that the invention is not limited thereto, as various changes in the minor details of construction, proportion and arrangement of parts may be resorted to

without departing from the spirit of the invention as defined in the appended claims.

I claim:

1. An article of the class described comprising a support, a radio cabinet borne thereby, a tubular member extending from said cabinet and a loud speaker unit carried by the upper end of said tubular member and having its open end directed upwardly.

2. An article of the class described comprising a support, a radio cabinet borne thereby, a slidible closure for said cabinet, a tubular member borne by said closure, and a loud speaker unit carried by the upper end of said tubular member and having its open end directed upwardly.

3. An article of the class described comprising a support, a radio cabinet borne thereby, a tubular member extending from said cabinet, said member having its upper end flared and a loud speaker unit seated in the flared end of said tubular member and having its open end directed upwardly.

4. An article of the class described comprising a support, a radio cabinet borne thereby, a slidible closure for said cabinet, a tubular member borne by said closure, said member having its upper end flared, a loud speaker unit nested in the flared end of said tubular member and having its open end directed upwardly, and a shade supported by said loud speaker unit and depending from the peripheral rim thereof.

In testimony whereof I affix my signature.

EWALD UFERT.
